BOLLARD

Lyn C. Hargraves, 745 Touraine, East Lansing, Mich.

Filed June 30, 1965, Ser. No. 85,951

Term of patent 14 years

(Cl. D71—1)

FIG. 1

FIG. 2

FIG. 3

FIG. 4

FIGURE 1 is a perspective view of a bollard, showing my new design;

FIGURE 2 is a front elevational view thereof;

FIGURE 3 is a cross-sectional view thereof taken on line III—III of FIGURE 2; and

FIGURE 4 is a top view thereof.

I claim:

The ornamental design for a bollard, as shown.
